UNITED STATES PATENT OFFICE.

WILLIAM T. RANDERSON, OF MUNHALL, PENNSYLVANIA, ASSIGNOR OF
ONE-HALF TO JAMES HORTON, OF MUNHALL, PENNSYLVANIA.

LUBRICANT-RECEPTACLE.

No. 819,454.

Specification of Letters Patent.

Patented May 1, 1906.

Application filed November 24, 1905. Serial No. 288,865.

To all whom it may concern:

Be it known that I, WILLIAM T. RANDERSON, a citizen of the United States of America, residing at Munhall, in the county of Allegheny and State of Pennsylvania, have invented certain new and useful Improvements in Lubricant-Receptacles, of which the following is a specification, reference being had therein to the accompanying drawings.

10 This invention relates to certain new and useful improvements in lubricant-receptacles; and the invention relates more particularly to a novel form of grease-cup.

The primary object of this invention is to provide an inexpensive and simple grease-cup adapted to be used in connection with journal-boxes or the like bearings where a shaft is to be lubricated or oiled.

Another object of this invention is the provision of novel means in connection with the grease-cup for agitating the contents of the cup and conveying the same to the shaft or element to be lubricated.

With the above and other objects in view the invention consists in the novel construction, combination, and arrangement of parts, to be hereinafter more fully described and then specifically pointed out in the claims, and referring to the drawings accompanying this application like numerals of reference designate corresponding parts throughout the several views, in which—

Figure 1 is a front elevation of my improved grease-cup. Fig. 2 is a vertical sectional view of the same. Fig. 3 is a plan of the receptacle proper. Fig. 4 is a side elevation of the cup as mounted in a journal box or bearing. Fig. 5 is a plan of a contact-head used in connection with the cup. Fig. 6 is a 40 side elevation of a spring adapted to support said head.

To put my invention into practice I employ a metallic receptacle 1, the periphery of which is provided with spirally - arranged grooves forming threads 2. The receptacle is provided with a central depending stem 3, a portion of the stem adjacent to the receptacle being hexagonal in cross-section, as at 4, to permit of a wrench being placed thereon to 45 permit of the cup being mounted in a journal-box or the like bearing. The remainder of the stem is tapered and provided with threads 4'. The stem is provided with a vertically-disposed opening or bore 5, and the bottom

of the receptacle is curved, as at 6, to convey 55 the contents of the receptacle toward the bore or opening 5 of the stem.

In connection with the receptacle I use a metallic cap or cover 7, which is cylindrical in form and has its sides provided with spirally-arranged grooves forming threads 8, which are adapted to engage the threads 2 of the receptacle 1. Centrally of the top of the cap is secured a depending coiled spring 9, which extends downwardly through the receptacle 65 1 and the bore 5 of the stem 3 and is provided with a metallic tapering contact-block 10 upon its lower end, said block being circular in cross-section and having its sides provided with a groove 11, in which the end of the 70 spring 9 is secured. The plug is preferably made of brass or the like durable material, while the cap 7 is preferably made of sheet metal, which is stamped to conform to the desired shape.

In Fig. 4 of the drawings I have illustrated a two-part journal-box 12, having a tapering opening 14, which leads to a shaft 15, journaled in the box 12. When the grease-cup is mounted in the opening 14 of the journal-box, the brass contact-block 10 of the cup is adapted to bear against the shaft 15, and as said shaft rotates it imparts a vibratory movement to said spring. The spring in turn is adapted to agitate the grease or contents of 85 the receptacle 1, causing the same to percolate through the opening or bore 5 of the stem into the opening 14 of the journal-box, where it contacts with the shaft 15 and thoroughly lubricates the same.

What I claim, and desire to secure by Letters Patent, is—

1. An oil-cup embodying a receptacle, a screw-threaded stem carried by said receptacle and having a centrally-disposed bore 95 formed therein, a cap adapted to fit upon said receptacle, a coiled spring carried by said cap and extending from within the receptacle through the said bore in the stem and below the end of the stem, a contact-block carried by said spring, the contact-block being disposed wholly below the end of the said stem, substantially as described.

2. A grease-cup embodying a receptacle, a centrally-disposed screw-threaded stem carried by said receptacle and having a centrally-disposed bore formed therein, a cap mounted upon said receptacle, a coiled spring carried

by said cap and extending downwardly through the bore of said stem, a tapering contact-block carried by said spring, said tapering block being formed with a groove to receive said spring, said block being disposed wholly below the bottom of the stem substantially as described.

3. A grease-cup embodying a receptacle, a stem carried by said receptacle, said stem having a bore formed therein, a cap mounted upon said receptacle, a spring carried by said

cap and extending downwardly through the bore of said stem and below the end of the stem, a removable contact-block carried by said spring, said block being disposed wholly below the stem substantially as described. 15

In testimony whereof I affix my signature in the presence of two witnesses.

WILLIAM T. RANDERSON.
